UNITED STATES PATENT OFFICE.

MILTON H. COOK, OF SAN FRANCISCO, CALIFORNIA, ASSIGNOR TO THE H. N. COOK BELTING COMPANY, OF SAN FRANCISCO, CALIFORNIA, A CORPORATION OF CALIFORNIA.

LEATHER PRODUCT.

Application filed June 26, 1926. Serial No. 118,764.

This invention relates to a leather product.

The present invention is concerned with means for utilizing a by-product incident to the production of leather and leather articles, and which product is now used mainly as fertilizer or is burned in the furnaces of the plants where it is produced. In the manufacture of leather articles large quantities of leather dust, shavings and small unuseful pieces of leather are produced, and it is the principal object of the present invention to provide means whereby this leather may be caused to serve a useful purpose in the manufacture of articles or as a coating or covering for articles used for various purposes. Such, for example, as the provision of a leather coating for belt pulleys, thus increasing the traction between the belt and the surface of the pulley.

The present invention contemplates the use of leather dust and fine leather particles which have been produced incident to the operation of leather cutting machines or directly from small unuseful pieces of leather, and which leather particles may be applied to surfaces or may be combined with other materials to form useful articles in manufacture.

30 The invention is illustrated by way of example in the accompanying drawings, in which:

Fig. 1 is a view in perspective showing a sheet of material embodying the present invention.

Fig. 2 is a view in transverse section through a leather shoe showing one application of the present invention to shoe construction.

40 Fig. 3 is a view in perspective showing an application of the invention to a belt pulley.

It is to be understood that the present invention is particularly concerned with the useful utilization of small waste leather particles. Two examples of such use are shown in the drawings, although other applications of the invention may occur to others skilled in the art, and it is to be considered that they are within the scope of the invention as here disclosed.

Referring to Figs. 1 and 2 of the drawings the leather produce is shown as a coating for sheets of celluloid and by which construction a leather coated water-proof prod-

uct is provided which is suitable for use as an intermediate sole in the manufacture of shoes, as shown in my Patent #1,309,461.

In Fig. 3 of the drawings, the application of the leather coating is shown as applied to the friction surface of a belt pulley and in which instance the use of belt dressings and like preparations is eliminated.

Referring more particularly to the drawing, 10 indicates a sheet of celluloid of any desired thickness, upon the opposite faces of which are applied coatings 11 and 12 of leather dust. This leather dust may be especially prepared for the present purpose by grinding up the leather, although in common practice it is possible to find large quantities of fine leather dust around the various machines used to cut the leather.

The dust is applied to the celluloid in the following manner: The celluloid is treated with a solvent or varnish, as by dipping, spraying or brushing. This may be done, for example, by dipping sheets of celluloid into a vat of the solvent or by running strips of celluloid through the vat by some mechanical means. The solvent may be spar varnish, acetone, ether or some other agent which will coat the celluloid, and which coating agent is mixed with alcohol in a proportion of approximately one to one; the alcohol being used to retard the coating action. Mixed with this solvent is a small amount of dissolved celluloid. This will give consistence to the solution and at the same time will prevent undue penetration of the solvent into the body of the sheet of celluloid. A mixture of alcohol and shellac or any combination of that nature may be used where a heavy coat of leather dust is required.

By treating the surface of the sheet of celluloid with the solvent it will be apparent that the surface of the celluloid will become "tacky". The leather dust may then be sprinkled or blown against the surface and will adhere thereto. This dust will then absorb a large amount of the moisture of the solvent which will be rapidly drying, due to the nature of the chemicals used. When the solvent is sufficiently dry to hold the dust the sheets of celluloid which have been thus coated are disposed between pressure plates and held in the desired shape until thoroughly dry. It may be desirable to add a

second coat of dust in order to increase the thickness of the product. This second coat of dust to be applied in substantially the same manner as the first. After the drying action has been completed it will be found that the opposite faces of the celluloid will bear a substantially permanent coating of leather and that these leather surfaces will form a suitable bond with other pieces of leather and cement. At the same time it will be understood that by treating the cement in this manner it is not liable to explode, although it would burn.

By reference to Fig. 2 an application of the present invention may be seen. Here the insole is indicated at 13, the lower or outer sole at 14 and the composition sheet of material at 15. By this construction it is possible to prevent moisture from penetrating through the sole 14 to the insole 13, and at the same time it is possible to glue the soles 13 and 14 to the leather surfaces of the insulating sheet 15 without difficulty. It is to be understood that this material lends itself readily to various uses other than in the manufacture of shoes, as, for example, insulating linings for leather goods and containers.

In applying a coating of the finely divided leather to metal surfaces, such, for example, as when applying a leather coating to the friction surface of a belt pulley the metal is first cleaned by the use of acetic acid or some other suitable cleansing material. It is then preferable to slightly roughen the surface and to permit the surface to dry during which time a slight oxidization will take place to form a thin coating of rust on the surface. When this is dry, shellac, glue,

or other binder may be applied to the surface, and while it is still wet the finely ground leather may be sprinkled or blown onto the surface or applied in any other convenient manner. After the binder has become dry, it has been found that the pulley possesses a friction surface over which the belt passes and with which the belt acquires increased traction.

It will also be understood that in certain instances it may be found advantageous to mix the leather particles with the material which is intended to act as a binder for the particles and to cause the particles to adhere to the surface.

While I have shown the preferred form of my invention, it is to be understood that various changes may be made in its construction by those skilled in the art without departing from the spirit of the invention, as defined in the appended claims.

Having thus described my invention, what I claim and desire to secure by Letters Patent is:

1. An article of manufacture comprising a sheet of celluloid, having a surface coated with granulated particles of leather, the celluloid material of the surface constituting a binder for holding the granulated particles together and to the said surfaces.
2. An article of manufacture comprising a sheet of celluloid having a surface thereof covered with particles of granulated leather, said particles being held upon the sheet of material by the celluloid at the surface, portions of the celluloid material at the said surfaces constituting a binder for the granulated leather.

MILTON H. COOK.
